Inventor:
Harry G. Norwood,

By Jas. L. Shadmore

Atty.

UNITED STATES PATENT OFFICE

HARRY G. NORWOOD, OF WASHINGTON, DISTRICT OF COLUMBIA, ASSIGNOR TO THEODORE F. VON DORN, OF NEW YORK, N. Y.

RAILWAY-RAIL ANCHOR

Application filed April 3, 1930. Serial No. 441,286.

This invention pertains to a novel, new and improved rail anchor especially designed to be secured to the base portion of a railway track rail, and adapted to engage with stationary parts of the railway road bed for the purpose of effectively preventing the longitudinal displacement or creeping action of the track rail which is likely to occur during the travel of the heavy rolling stock thereover.

The main object of the invention is to provide a durable, simple, practical, economical and efficient rail anchor, or anti-creeper, possessing a maximum of strength, which when properly and fixedly applied to the base portion of a track rail will effectively resist and prevent the creeping tendency of the said rail.

Another object of the invention is to provide an improved rail anchor formed from a single piece of high grade spring steel, hot or cold, but preferably heat treated steel, which under any and all conditions will serve to prevent any tendency of the creeping action of the track rail toward an adjacent cross-tie.

A further object of the invention is to so construct my novel rail anchor that any tendency of the track rail to creep longitudinally will serve to force the body portion thereof outwardly, thus simultaneously forcing the rail clamping members inwardly, thereby causing the gripping parts of the anchor to intensify its clamping action in contact with the rail base to which the said anchor is secured.

The foregoing and such other objects as may appear from the ensuing description are accomplished by the construction, arrangement, location and combination of the several parts hereinafter more fully described, illustrated in the accompanying drawings and particularly pointed out in the claims appended hereto, it being understood that slight changes in the precise formation, proportions and minor details of construction may be resorted to without departing from the spirit or sacrificing any of the advantages of the invention.

In the accompanying drawings forming

a part of this specification it will be seen that:

Figure 1 is a plan showing a portion of a bar or steel plate from which my improved anchor is formed.

Figure 2 is a side elevation of the rail anchor embodying my invention, showing the anchor secured to the base of a track rail in contact with a cross-tie with the track rail in cross-section, and the cross-tie broken away.

Figure 3 is a plan of the anchor shown in Fig. 2, showing the track rail and cross-tie broken away.

Figure 4 is a side elevation showing the anchor detached and removed from the track rail.

Figure 5 is a plan of a slightly modified form of rail anchor, and

Fig. 6 is an end elevation of the form of anchor shown in Fig. 5.

In the embodiment of my invention as illustrated, it will be seen that Fig. 1 indicates a portion of a bar or plate of spring sheet steel from which the novel anchor is formed showing a line 3 designating the line of separation of each anchor, a space 4 showing the maximum amount of waste material, that occurs in the formation of each anchor, and lines 5 and 5' to denote the slits formed through the body portion of the anchor for the purpose hereinafter described.

Referring now to Fig. 2 it will be seen that the anchor is shown applied to the base of a standard track rail 6, the said anchor being designated as an entirety by the letter B, and is formed from a high grade of spring sheet steel, possessing the requisite thickness and dimensions to furnish a maximum degree of strength, by pressing or stamping the sheet in suitably prepared dies, and at the upper part thereof, at one end portion thereof, is formed an overhanging or overlapping clamping jaw member 7, while at its opposite or other end portion is formed an upwardly extending clamping or gripping member 8, said members 7 and 8 being adapted to tightly grip and clamp the base portion of the track rail and each side thereof, respectively.

The body portion 9 of the anchor is provided intermediate its height with two slits 10

10 and 10' formed therethrough, each slit extending from a point intermediate the ends of the anchor to each outer end thereof, and during the stamping or pressing operation that portion of the body portion below each of the said slits 10 and 10' is forced outwardly from the central portion of the body at each of its outer ends forming the laterally extended members 11 and 11' adapted to engage with the cross-tie, when the anchor shall have been properly secured to the base of the track rail 6.

It will be readily perceived that when the anchor has been properly and fixedly applied to the base portion of the track rail with the members 11 and 11' resting in engagement in the cross-tie 12, as shown in Fig. 3, the greater the tendency of the track rail to creep, caused by the strain of the heavy rolling stock thereover, the more intense is the pressure of the members 11 and 11' against the cross-tie thereby forcing the central portion of the body outwardly, thereby imparting a vertical shackle grip, caused by the tendency of the device to tip forward at the top when the rail advances initially, and simultaneously causing an inwardly movement of each clamping end of the anchor, thus intensifying the gripping power of each clamping member in contact with the track rail base.

In applying the anchor to the base of the track rail it is simply necessary to place it by hand on one side of the rail base with its clamping jaw member 7 overlapping the upper inclined surface of said base; with the upper face of the clamping member 8 resting in contact with the lower face of the base of the rail, then by driving the anchor endwise from the left hand end thereof, as shown in the drawings, with the usual sledge or maul employed for like purposes, until the inner face of the clamping member passes the other side of the rail base, when the said clamping member 8 will immediately snap upwardly and tightly grip and clamp with the edge of the rail base, all of the parts in contact with said base being under intense gripping action with the base portion of the track rail.

The anchor may be easily removed or detached from the base of the rail by striking the upper face of the clamping member 8 downwardly and then driving it off from the right hand end portion of the anchor, as will be readily understood.

It will be readily evident that this particular formation of anchor may be readily applied from either side of the track rail, and that it may be readily detached from the rail and repeatedly used, thereby increasing its longevity.

The slightly modified form of anchor, such as is shown in Figs. 5 and 6 shows the outwardly disposed members 13 and 13' stamped out laterally from the lower end portion of the body of the anchor, each of

said members being formed with a curved extended outer face 14 and 14' adapted to contact with the cross-tie, said formation of each outer face serving to prevent all damage to the cross-tie by the cutting in, scraping or otherwise defacing of the tie.

It will also be understood that by this particular construction of anchor with the lowermost depending portion of the anchor in contact with the tie, that all tendency of the bearing points of said anchor against the tie to rise above the tie, and to contact with the rail seat plate, caused by the up and down movement of the rail during the passage of the heavy rolling stock thereover will be safely avoided.

Having thus described my invention what I claim and desire to secure by Letters Patent is:

1. A railway rail anchor formed from a single piece, comprising a rail clamping member at each end portion thereof, a body portion, and outwardly extended members stamped from the lower end portion of said body and extending from the central portion of the body to each of its outer ends.

2. A rail anchor formed from a single piece of high grade spring steel formed with a rail gripping member at each end portion thereof, a body portion formed with slits therethrough, said slits extending from each outer end to a point intermediate its length, and laterally extended members formed from the bottom portion of said body adapted to rest in contact with a cross-tie.

3. A rail anchor composed of a single piece of spring sheet steel formed with a rail clamping member at each end portion thereof, a body portion provided with slits therethrough, said slits extending from a point intermediate its length to each outer end, and outwardly extended members formed from the bottom portion of said body and extending from the central portion of the body to each of its outer ends.

4. A rail anchor formed from a single piece of metal, comprising a rail clamping member at each end portion thereof, a body portion slit therethrough intermediate its height, said slits extending from the central portion of the body to each outer end, and outwardly extended members disposed longitudinally formed from the bottom portion of the body and extending from its central portion to each outer end.

5. A rail anchor formed from a single piece, comprising a rail clamping member at each of its end portions, a body portion slit longitudinally intermediate its height, said slits extending from each end to a point intermediate its ends, and outwardly disposed longitudinal members formed from the bottom portion of the body, and adapted to contact with a cross-tie.

HARRY G. NORWOOD.
